CLAIM

The ornamental design of a convex rectangular pocket with bag portion, as shown and described.

DESCRIPTION

This application is related in subject matter to U.S. patent application Ser. No. 29/122,420, filed Apr. 26, 2000, entitled “Convex Compacted Square Bag”, now U.S. Pat. No. Des. 441,188.

FIG. 1 is a top plan view of a convex rectangular pocket with bag portion, attached to at least a portion of a bag and illustrated with an access shown in broken lines;

FIG. 2 is a bottom plan view thereof where only a portion of the bag is viewable;

FIG. 3 is a right side elevational view of FIG. 1; the left side being a mirror image thereof;

FIG. 4 is a top plan view for a convex rectangular pocket with bag portion as in FIG. 1, showing an alternative arrangement with multiple fabrics having different shading including the major circular portion with shading indicating the first preselected fabric, the minor circular portion with shading indicating the second preselected fabric.

FIG. 5 is a top plan view of a convex rectangular pocket with bag portion in a rectangular embodiment attached to at least a portion of a bag and illustrated with an access shown in broken lines;

FIG. 6 is a bottom plan view thereof from which only a portion of the bag is viewable;

FIG. 7 is a side elevational view of FIG. 5; and,

FIG. 8 is a top plan view for a convex rectangular pocket with bag portion as in FIG. 5, showing an alternative arrangement with multiple fabrics having different shading including the major circular surface with shading indicating a first preselected fabric, the minor circular surface with shading indicating a second preselected fabric.

Any broken lines are to show the environment only and are not part of the claimed design.

1 Claim, 5 Drawing Sheets
